UNITED STATES PATENT OFFICE.

ROBERT D. GREEN, OF LOWNDES COUNTY, MISSISSIPPI.

DESIGN FOR GRANGER'S BADGE.

Specification forming part of Design No. 7,598, dated July 28, 1874; application filed June 23, 1874.
[Term of Patent 3½ years.]

To all whom it may concern:

Be it known that I, ROBERT DERRETT GREEN, of Lowndes county, in the State of Mississippi, have originated and designed a new Pattern of Badge or Emblem for the use of the society called Grangers or Patrons of Husbandry, of which the following is a full, clear, and exact description, reference being had to the accompanying drawing making part of this specification.

Figure marked 1 represents the letter G, composed of a portion of a wreath of flowers, a bee-hive, and dove. Rustic letters, marked

2 2, placed on each side of letter G, stands for Patrons of Husbandry. Fig. 3 is name-plate for name of State lodge to be engraved thereon. Fig. 4 represents a cotton-bale. Fig. 5 represents the American eagle holding in his bill a plow, marked by Fig. 6.

I claim—

The design for a Granger's badge, substantially as herein described and shown.

ROBERT DERRETT GREEN.
